(57) **CLAIM**

The ornamental design for a mounting plate, as shown and described.

DESCRIPTION

FIG. 1 is a top perspective view according to a first embodiment of a mounting plate showing our new design;

FIG. 2 is a top plan view thereof;

FIG. 3 is a bottom plan view thereof;

FIG. 4 is a bottom perspective view thereof;

FIG. 5 is a front elevational view thereof;

FIG. 6 is a rear elevational view thereof;

FIG. 7 is a left side elevational view thereof; and

FIG. 8 is a right side elevational view thereof.

FIG. 9 is a top perspective view according to a second embodiment of a mounting plate showing our new design;

FIG. 10 is a top plan view thereof;

FIG. 11 is a bottom plan view thereof;

FIG. 12 is a bottom perspective view thereof;

FIG. 13 is a front elevational view thereof;

FIG. 14 is a rear elevational view thereof;

FIG. 15 is a left side elevational view thereof; and,

FIG. 16 is a right side elevational view thereof.

In all embodiments, the broken lines show portions of the mounting plate and form no part of the claimed design. All contour lines shown in each drawing are lines representing surfaces of the solid body, and form no part of the subject design.
